UNITED STATES PATENT OFFICE.

ALFONSO A. RICHARDSON, OF NEW YORK, N. Y.

BED.

1,301,973.

Specification of Letters Patent. Patented Apr. 29, 1919.

Continuation of application Serial No. 13,818, filed March 12, 1915. This application filed August 28, 1916. Serial No. 117,215.

To all whom it may concern:

Be it known that I, ALFONSO A. RICHARDSON, a citizen of the United States, residing at New York, State of New York, have invented certain new and useful Improvements in Beds, of which the following is a specification.

This invention relates to beds, and one of the objects of the same is to provide a structure such that when a person reclines thereon, the bedding supporting medium, such as the usual spring construction, is automatically made tauter by the weight of the person. Another object is to provide a hammock-like structure which does not sag like a hammock, and is therefore more in the nature of a bed. Other objects are to provide a simple, practical and efficient bed.

These being among the objects of the present invention, the same consists of certain features of construction and combinations of parts to be hereinafter described and then claimed with reference to the accompanying drawings illustrating desirable embodiments of the invention, and in which—

Figure 1 is a side elevation of a bed constructed in accordance with the present invention, parts of the bed springs being shown in dotted lines;

Fig. 2 is a plan view thereof, parts being in dotted lines;

Fig. 3 is an end elevation;

Fig. 4 is an enlarged central transverse section;

Fig. 5 is a detail in elevation, partly in section, showing one of the joints of the structure;

Fig. 6 is a detail perspective view of the spreader; and

Fig. 7 is a modification in which the improvements are shown as supported within an ordinary bedstead.

The frame of the bed is preferably composed of metallic tubing and comprises bed frame sections 10, 11, having side bars 12, 13, 12^a and 13^a. The side bars are connected by transverse connecting bars 14, 14^a, at the top of the bed structure, and 15 at the bottom of the structure. The bottom of the structure as, for instance, the transverse connecting bars 15, is preferably provided with casters or the like, shown herein as consisting of anti-friction sleeves or rollers 16. Attached to the upper connecting bars

14, 14^a, are the opposite ends of the bedding supporting medium 18, which may be in the nature of the usual spring mattress.

The side bars of the bed frame sections are connected together at their opposite ends 60 by means of parallel bars 19, 20, which constitute fulcrum members and form side bars for the bed. These side bars are connected with the bed frame sections 10, 11, by knuckle joints 21 shown in detail in Fig. 5, 65 a stem 22 constituting one member of the knuckle joint and another stem or arm 24 constituting the other member, the stem 22 being inserted in the preferably hollow bar or fulcrum member and being pinned thereto 70 at 23, while the other member 24 is provided with a sleeve 25 for receiving the adjacent side bar of the bed frame section, said sleeves being connected to the latter by pins 26. The stems or arms or the like 22, 24, are 75 connected together by fulcrum pins 27, so that there will be four of these knuckle joints, or any suitable number, connecting the movable bed frame sections with the fulcrum members 19, 20. The side bars of 80 the bed frame sections are bent at 28 so as to provide paired long arms 29, 30, which extend in opposite direction and are inclined downwardly so that the pairs cross each other at 31. It will be seen therefore, that the bed 85 frame sections constitute levers extending from end to end, with short arms above the knuckle joints and long arms below and extending beyond them. In other words, the bed frame sections are pivotally or movably 90 connected with the fulcrum members on which they fulcrum, and the outer lower end of one bed frame section is disposed under the upper outer end of the other frame section.

Preferably the bed frame sections are provided below the bends 28 with joints at 34 formed by telescoping the long arms of the levers 29, 30 into the hollows of the bends, the bed frame sections being preferably hollow. In order to limit the downward movement of the bed structure when the weight of a person is imposed upon the same by their reclining upon the bedding supporting medium, the bed frame sections are provided at opposite sides at 35, 36, respectively, with stop lugs, the stop lugs 35 coming in contact with the side bars of the relatively movable bed frame section, while the stop lugs 36 act in a similar manner, 110

there being stop lugs at both sides of the point of crossing 31 of the bed frame sections.

It will be seen that the weight of a person reclining upon the bedding supporting medium 18 will act to lower the latter and the entire structure, due to the fact that a purchase is obtained at each lower outer end of the bed frame sections, with the result that the long arms of the levers extending upwardly toward the knuckle joints will act upon the shorter arms of the levers 32, 33, extending above said joints, thereby tending to move said short arms away from each other, thereby stretching the bedding supporting medium longitudinally of the bed structure. The object of this is to prevent undue sagging of the bedding supporting medium by automatically tightening the same by the weight of the occupant.

In some cases the above described construction or its equivalent may be all that is necessary to meet the requirements, but preferably means are provided for stretching the bedding supporting medium transversely as well as longitudinally. To this end a spreader 37 is employed, which may consist of strips or rods of spring metal bent into closed loop form, as shown clearly in Figs. 2 and 6. This spreader extends transversely of the mid-length of the bedding supporting medium and the ends thereof are secured to rather stiff side spring brackets 38. The structure composed of the said spreader and the brackets is preferably formed of continuous lengths of spring wire so as to provide spring jaws or holding members 39 at the outer lower ends of the spring brackets and bent up springs 40 of any suitable shape. Preferably at the outer ends of the spreader 37 clips 41 are fastened, at the points from which the spring brackets 38 extend downwardly, said clips being formed preferably of sheet metal bent around the parts to which they are applied, said clips being provided with outwardly facing attaching hooks 41^a. In use the spring jaws or clips 39 are sprung over the side bars or fulcrum members 19, 20, so as to act as a rest or support, and the brackets 38 extend upwardly toward the bedding supporting medium, with the spreader 37 extending between them and just underneath the bedding supporting medium so that the downward pressure on said medium will be transmitted to or resisted by the spreader structure. It will be seen that in this way the spreader structure constitutes a transverse bridge for the auxiliary support of the occupant of the bed, the springs 40 acting to give additional spring support for the occupant. When the spreader is in position, the attaching hooks or clips 41^a, which face outwardly, will be brought into engagement with side stiffening rods 41^b,

41^b, located at the sides of the bedding supporting medium. These stiffening rods or bars need only extend a part of the length of the bed, and they constitute tension members for the purpose of placing lateral tension upon the bedding supporting medium, to which end the latter may be provided with transverse spring connections, such as 37^a, extending between the side edges of said medium. It will be noticed that if the side bars of the transverse spreader 37 are pressed together, they will act to spread or extend the bedding supporting medium transversely, through the medium of said side bars and the tension rods 41^b. In this way the longitudinal tension on the bedding supporting medium is supplemented by a transverse tension.

The means for setting up this transverse tension through the spreader 37 may consist of guy lines 42, 43, there being one pair 42 of lines and another pair 43. The ends of the guy lines 42, 43, are respectively attached to the opposite ends of the bed frame sections at the cross bars 14, 14^a, and to the spreader 37, said lines crossing one side of the spreader and being attached to the remote side. It will be seen therefore that when the bedding supporting medium is subjected to the weight of a person thereon, the frame of the bed is extended longitudinally, which acts upon the guy lines so as to pull the side portions of the spreader together, thereby extending said spreader in the direction of the width of the bed, which will result in stretching the bedding supporting medium transversely.

An adaptation of the invention to an ordinary bedstead is illustrated in Fig. 7. Like parts of the described device bear similar numerals in this figure. The bedstead 44 may support the described structure between its head and foot pieces and the side rails, as shown, that is to say, the described construction of bed may be hung from the bedstead 44, so that it is more in the nature of a hammock. To this end the end rails 45, 46 of the bedstead are engaged by hooked hangers or suspenders 47, 48, which are movably connected with the outer lower ends of the bed frame sections 10, 11.

It is obvious that the invention is susceptible of modification, as parts may be omitted, parts added, and parts substituted without departing from the scope of the claims.

What I claim as new is:—

1. In a bed, the combination of a bed frame which is expandible and contractible, and comprising opposite connected lever devices and a common fulcrum member at each side of said frame for said devices, each of the levers of said lever devices comprising a long arm and a short arm, said short arm being extended outwardly from said long

- arm at a substantial angle, and said fulcrum member being opposed to said lever at a point adjacent the angle formed by its said arms, and a bedding supporting medium connected with portions of said lever devices and adapted to be automatically expanded by said frame and stretched longitudinally when a suitable weight is imposed on said medium.
2. In a bed, the combination of a bed frame which is expansible and contractible longitudinally, a longitudinally expansible spreader extending transversely of and connected with said frame, and a bedding supporting medium connected with portions of said frame and adapted to be automatically expanded by said frame and spreader and stretched in two transverse directions when a suitable weight is imposed on said medium.
3. In a bed, the combination of crossed substantially rigid lever members at both sides of the bed, the same being fulcrumed together above their crossings, means for connecting said members across the bed, and a bedding-supporting medium connected with the said connecting means and adapted to automatically exert tension on said members to stretch said medium, under weight imposed on said medium, and a longitudinally expansible spreader extending transversely of and connected with said lever members and adapted to exert outward thrust on said supporting medium, under the imposition of said weight.
4. In a bed, the combination of crossed substantially rigid lever members at both sides of the bed, the said members being fulcrumed together above their crossings, means for connecting said members across the bed, and a bedding-supporting medium connected with the said connecting means and adapted to automatically exert tension on said members to stretch said medium, under weight imposed on said medium, and a longitudinally expansible spreader loop extending transversely of and connected with said lever members and guy lines connecting the ends of said lever members respectively with the remote sides of said loop, whereby said loop is adapted to exert outward thrust on said supporting medium under the imposition of said weight.
5. In a bed, the combination of a bed frame which is expansible and contractible longitudinally, a bedding-supporting medium con-
- nected with the ends of said frame, and a longitudinally expansible spreader loop extending transversely of and connected with said medium to produce side thrust on the 60 sides of said medium, whereby a weight imposed on said medium causes the stretching of said medium longitudinally and transversely.
6. In a bed, the combination of a bed frame 65 which is expansible and contractible longitudinally, a bedding-supporting medium connected with the ends of said frame, and a longitudinally expansible spreader loop extending transversely of and connected with 70 said medium to produce side thrust on the sides of said medium, and guy lines connecting the ends of said frame respectively with the remote sides of said loop, whereby a weight imposed on said medium causes the 75 stretching of said medium longitudinally and transversely.
7. A bed, comprising crossed lever members, and connections for said members comprising stiff means with which said members 80 are pivotally connected and restraining means consisting of stop lugs coöoperating with said members to prevent collapse of said bed, said members being disconnected at their points of crossing.
8. A bed, comprising two frame-sections formed in closed oblong shape, the opposite side portions of each of said sections being bent at a substantial angle and in the same direction as the opposite side portions of the 90 other section and crossing each other, said sections being disconnected at their crossings, means for connecting said side portions above their crossings, the angular bends of said sections being located directly below 95 their points of connection with said connecting means.
9. In a bed, the combination with rigid supporting means, of a bed frame, comprising relatively movable sections, arranged 100 within said means and loosely suspended therefrom by said sections, said frame being expansible and contractible, and provided with a bedding supporting medium connected with portions of said frame and adapted to automatically expand said frame and stretch said medium when a suitable weight is imposed on said medium.
